UNITED STATES PATENT OFFICE.

HENRY B. PETIT, OF DETROIT, MICHIGAN, ASSIGNOR TO GEORGE M. HOLLEY, OF DETROIT, MICHIGAN.

AIR VALVE FOR CARBURETORS.

Application filed April 11, 1927. Serial No. 182,643.

The object of this invention is to provide a simple weighted air valve which will not require a dash pot to prevent pulsation. Other objects are to provide an air valve which will 5 provide the intensified compensation which is necessary to ensure steady low speed running when no bypass is provided around the throttle.

Another object is to provide an air valve 10 which will, at wide open throttle, offer a minimum resistance to the air flow, so that the carburetor operates practically as a plain tube carburetor. Finally, the object is to obtain at intermediate throttle positions 15 (when the car is being driven through the driving range) the necessary minimum fuel consumption, without which a carburetor is unsalable.

This intermediate lean mixture has heretofore been usually obtained by mechanical devices operated by the throttle, and known as "economizers". The defect of such throttle controlled economizers is that they come into operation at a definite throttle position, 25 whereas an air valve gives a definitely richer mixture during the period immediately after the opening of the throttle, that is during the time the engine is accelerating.

However, the chief object of this invention 30 is to provide an air valve in which the air flow itself automatically stabilizes the air valve at high air velocity, eliminating the need for a dash pot.

Figure 1 shows the air valve applied to a 35 vaporizer of the type in which a hot rich mixture is diluted with cold air.

Figure 2 is a cross section on section 2-2 of Figure 3.

Figure 3 is a partial sectional elevation on 40 plane 3-3 of Figure 1.

Figure 4 shows an alternative construction.

In the figures, A is the air entrance, B is the air valve, C is the stop limiting the opening movement of the air valve. D is the 45 starting (choke) valve, E is the Venturi tube mixing chamber. F is the entrance for the hot rich mixture into the mixing chamber E. G is the throttle valve located in the mixture outlet. J J are the pivots or supports for 50 the air valve B. K is the distance this support is located below center. L is the width of the widest portion of the air valve. In the preferred construction I have found that with a valve 1.283" dia., K=.046" and 55 L=13/16", that these proportions give the

above described result. The angle M, which is the angle the bottom face of the air valve B makes with the horizontal, I have found should be 25°. The importance of these inclined flat surfaces in ensuring stability is 60 emphasized. The clearance between the valve B and the air entrance A should be .015" all around, or .030" in diameter, in order that there should be 1" depression in F on idling.

It will be noted (see Fig. 1) that the widest portion of the air valve assumes a position which offers the least obstruction when the air flow is greatest. That is to say, the air valve is more or less stream lined, the thin 70 edge facing down stream, although obviously a coil spring could be substituted for gravity or to assist the force of gravity.

In Figure 4 the air valve B has been more scientifically stream lined on the down stream 75 side and moved up next the rich mixture entrance to the mixing chamber, and the venturi E removed so that the stream lined air valve itself will take its place and forms a mixing chamber of somewhat venturi form, 80 but the flat faces on the upstream side of the air valve are retained.

Operation.—In Figures 1, 2, and 3, when the engine is idling, the air valve B is substantially in a vertical position when the 85 throttle G is opened and the depression in F increases above 1" of water the valve B slowly opens gradually admitting more air. When the throttle G is thrown wide open the valve B takes the position shown in Figure 1. 90 When it is in this position, if it is moved out of the position shown it immediately returns to this position. That is to say, it is positively held in a position parallel to the air stream, and may be said to be in a position of stable 95 equilibrium.

What I claim is:—

1. In a carburetor, an air passage, a wedge-shaped weighted air valve pivotally supported in the air stream and adapted to take a position parallel to the air stream when the air valve is at maximum with the thinner edge of the air valve facing down stream.

2. In a carburetor, an air passage, a wedge-shaped weighted air valve pivotally supported in the air stream and adapted to take a position parallel to the air stream when the air valve is at maximum with the thinner edge of the air valve facing down stream, the bottom of said air valve being 105 110

bounded by two flat surfaces symmetrically inclined to the axis of said air valve.

3. In a carburetor, an air passage, a wedge-shaped air valve pivotally supported in the air stream on a horizontal axis, so that the greater portion of the surface is located above said axis, and the greater mass of the air valve is located below the said axis, the bottom of the valve being wedge-shaped, where-

by the air valve automatically takes a position parallel to the air stream with the thinner edge down stream when the air velocity is at a maximum and automatically takes a position substantially normal to the air velocity when the air flow is at a minimum.

In testimony whereof I affix my signature.

HENRY B. PETIT.
